CLAIM

The ornamental design for a combined water control handle and escutcheon, substantially as shown and described.

DESCRIPTION

FIG. 1 is a right side elevational view of a combined water control handle and escutcheon, showing our new design, the left side being a mirror image of the right side shown;

FIG. 2 is a top plan view thereof;

FIG. 3 is a bottom plan view thereof;

FIG. 4 is a front elevational view thereof; and,

FIG. 5 is a rear elevational view thereof.
